UNITED STATES PATENT OFFICE.

EUGENE GREGORY, OF ANN ARBOR, MICHIGAN.

DESIGN FOR A FINGER-TIP PENCIL.

Application filed March 5, 1926. Serial No. 16,796. Term of patent 3½ years.

To all whom it may concern:

Be it known that I, EUGENE GREGORY, a citizen of the United States, residing at Ann Arbor, in the county of Washtenaw and State of Michigan, have invented a new, original, and ornamental Design for Finger-Tip Pencils, as shown in the accompanying drawing, forming part of this specification.

Fig. 1 of the drawing shows a perspective

view of the design for a finger tip pencil.

Fig. 2 is a front end view of the finger tip pencil.

Fig. 3 is a rear end view thereof.

I claim:

The ornamental design for a finger tip pencil substantially as shown.

EUGENE GREGORY.
